UNITED STATES PATENT OFFICE

LOUIS LINK, OF NEW YORK, N. Y., ASSIGNOR, BY MESNE ASSIGNMENTS, TO NASHUA GUMMED & COATED PAPER CO., OF NASHUA, NEW HAMPSHIRE, A CORPORATION OF MASSACHUSETTS

GUMMED TAPE SERVING MACHINE

Application filed October 15, 1927. Serial No. 226,366.

This invention relates to tape serving machines, and more particularly to machines for feeding, moistening and cutting gummed tape, and comprises all improvements over 5 the prior art which are disclosed in this application.

One object is to provide a simple and effective construction which can be made at low cost. Another object is to provide a 10 shear having a lower movable blade which is pressed laterally against the fixed blade in a suitable manner to cut properly. Another object is to provide an operating lever which by a single direction movement, first feeds 15 and moistens, and then cuts the tape into desired lengths, the lever being returned to original position by a spring and the cutting device being returned to non-cutting position by another spring. Another object is to provide 20 very simple effective tape feed rollers. Another object is to provide a cover which conceals much of the mechanism and which also presses the tape down onto the moistening device. Another object is to provide a 25 simple effective adjustable tape and tape roll guide device to accommodate and properly position tape rolls of different widths. Another object is to provide a tape roll guide and presser arm device to aid in properly 30 positioning and holding the tape roll.

The above and other objects which will hereinafter appear, are attained by the new and useful improvements disclosed in this 35 application. To enable others skilled in the art to fully understand the essential characteristics of the improvements, drawings illustrating one mode of carrying out the invention have been annexed as part of this disclosure.

Fig. 1 is a plan view of a machine for carrying out the invention, with certain parts removed for clearness.

Fig. 2 is a right side elevation of Fig. 1 with 45 the right side plate removed, and certain parts in section.

Fig. 3 is a fragmental front elevation illustrating the shear in full cutting position.

Fig. 4 is an enlarged sectional view of the 50 adjustable paper guide on line 4-4 of Fig. 1.

Fig. 5 is a right side elevation of the machine.

Fig. 6 is a front elevation of the machine with the cover swung up and with the water tank removed.

Fig. 7 is a sectional view on line 7-7 of Fig. 2.

Fig. 8 is a perspective view of the pawl and release mechanism.

The main frame of the machine comprises 60 side members 1, 2 and bottom members 3, 4. Side members 1, 2 are preferably of sheet metal and have supporting feet 5 provided with rubber members 6. Side members 1, 2 are connected together at the front by means 65 of the bottom member 4 having lugs 7 connected to members 2 and lug 8 connected to member 1. Screws 9, 10, together with spacing pins 11, 12 connect the sides 1, 2 at other places in a well known manner. Bottom 70 member 3 has lugs 13, 14 engaged about pin 12 and then extends down and forward as shown in Fig. 2, terminating adjacent fixed shear blade 15 where it is connected by screws 16 to lugs 17 of side members 1, 2. Also secured by screws 16 is a tape guide plate 18 having its central portion spaced above member 3 to provide passage for the tape, and having its rear curved upward to form 75 guard 19.

Member 3 is cut away at 20, 21 to permit guide discs 22, 23 to be adjusted to different positions on pin 24 pivoted in side members 1, 2. As best seen in Fig. 4, pin 24 has a plurality of annular grooves 25 to accommodate balls 26 pressed by springs 27 in holes 28 extending diametrically in discs 22, 23. By pushing discs 22 and 23 longitudinally of pin 24, balls 26 will move out of certain grooves 25 against action of springs 27 and when the discs again reach a position over any of the grooves 25, the balls 26 will be snapped into locking position again by springs 27.

Pivoted to pin 12 by ears 29, is a roll positioner and guide in the form of a presser arm 30 carrying a pin 31 and adjustable discs 32, 33 similar to pin 24 and discs 22, 23. Pin 31 of this presser arm 30 engages a tape roll 34 somewhat to the rear of its top and by action of spring 35 presses the tape roll 34 down 100

and forward against pin 24, the discs 22, 23, 32, 33 having been adjusted to span the tape roll. The tape roll is thus held in a constant position and alignment without being permitted to move about while the tape unwinds.

Fixed shear blade 15 is secured to side members 1, 2 by having one end 36 rectangular in shape and entering a corresponding slot in ear 37 on side member 2. The other end is connected by bolt 38 to ear 39 on side member 1. The movable shear blade 40 is also mounted at one end on bolt 38, but is freely pivoted thereon. Blade 40 has a slot 41 engaged by pin 42 on shear lever 43 which 10 lever is pivoted to ear 44 of member 4 by bolt 45. Shear lever 43 has an angled extension 46 adapted to be engaged by abutment pin 47 or like reinforcement mounted in operating lever 48. Spring 49 extends between 15 shear lever 43 and the pin or the like 50 in such a direction as to pull shear lever 43 and consequently blade 41, laterally, to at all times maintain a good cutting action of 20 blades 40, 15, and at the same time to normally act on shear lever 43 to cause blade 41 to resume non-cutting position. It will be seen that as shear lever 43 travels along 25 blade 40, the point of lateral pull on blade 40 gradually shifts in the direction of the free 30 end of the blade 40 as the point of cutting action approaches the same free end. Thus at all times good cutting action of the shear blades is maintained.

Removably resting on member 4 is a water tank 51 having a downwardly extending tongue 52 bent at 53 to provide a seat for the end of brush 54. Lip 55 extends as shown toward brush 54. It will be seen that just enough room is provided for inserting brush 40 into tank 51, and no more, to prevent undue tendency of water slopping out of the tank when being handled. Water ascends brush 54 for moistening the tape.

Guide plate 18 is cut away at 56 to accommodate knurled feed roll 57 mounted on pin 58 which is sufficiently thin and inherently resilient to press feed roll 57 sufficiently firmly against another knurled feed roll 59 extending up through slot 60 in member 3. 45 Lower feed roll 59 is secured on a shaft 61 operated by gearing as shown, from gear 62 rigidly secured to ratchet 63 and both mounted to freely turn on shaft 64. Rigidly secured on shaft 64 is a ratchet arm 65 carrying 50 a pivoted pawl 66 normally urged by spring 67 into engagement with ratchet 63. When pawl 66 moves to a certain position, it strikes a pin 68 fixed in side 1 which causes pawl 66 to be disengaged from ratchet 63, thus ceasing 55 to turn knurled feed roll 59.

Secured to the protruding non-circular end 69 of shaft 64 is the operating lever 48, previously mentioned, secured by taper pin 70 or other suitable means. Mounted in a curved 65 slot 71 is a headed limit bolt 72 carrying

pointer 73, limit bushing 74, knurled adjusting nut 75, and cover nut 76. Thus by means of bolt 72, the upward movement of operating lever 48 can be limited as desired. Lever 48 is normally urged upward against 70 bushing 74 by means of coil spring 77, see Figs. 2 and 7, coiled around shaft 64 and having one end secured to pin 11 and its other end secured to pin 78 on ratchet arm 65. Pawl actuating spring 67 also has one end 75 connected to this pin 78.

Pivoted on pin 58 is a cover member 79 having a sloping guide portion 80 which is adapted to rest on top of brush 54.

Operation.—Presser arm 30 is lifted back, 10 tape roll 34 is placed on bottom 3 with the free end of tape extending between pin 24 and bottom 3. On release of arm 30, roll 34 tends to be pressed into position as shown in Fig. 2 against pin 24. The tape end is led 15 between knurled feed rolls 57, 59 by pressing down on operating lever 48 which feeds the tape out between parts 18 and 3, to fixed shear blade 15. Operating lever 48 is then released and spring 77 swings it up until its strikes 20 limit bushing 74. By means of knurled nut 75, bolt 72 carrying limit bushing 74 is adjusted for any length of cut desired. Tank 51 is filled with water and brush 54 inserted 25 and the tank is placed in position in the machine, which is now ready to feed, moisten and cut strips of gummed tape of uniform predetermined length.

By depressing operating lever 48, since pawl 66 is in engagement with ratchet 63, the 100 tape is fed forward until one end of pawl 66 strikes against fixed pin 68, causing the pawl to be released from ratchet 63, and the feed of the tape now ceases although lever 48 is pressed on down. Presently pin 47 of 105 lever 48 engages end 46 of shear lever 43 and swings movable shear blade 40 to sever the tape. On release of operating lever 48, the operating lever is first moved upward by action of both springs 77 and 49 until shear 110 lever 43 returns to normal position. From this point upward, the operating lever 48 is moved by spring 77 alone, until the lever strikes limit bushing 74, when the machine 115 is again ready to feed, moisten and cut another strip of tape of the same length as the first one. In operation, the strip of tape is pushed part way over the moistening brush 54 and when grasped by the fingers and pulled out to be used, the remainder of the 120 strip is moistened as it passes over brush 54.

The invention may be embodied in other specific forms without departing from the spirit or essential characteristics of the invention, and the present embodiment is therefore to be considered in all respects as illustrative and not restrictive, the scope of the invention being indicated by the appended claims rather than by the foregoing description, and all changes which come within the 125 130

meaning and range of equivalency of the claims are therefore intended to be embraced therein.

I claim :

5. 1. A gummed tape serving machine comprising, a tape shear device having a fixed blade and a movable blade pivoted adjacent one end of the fixed blade, and operating means for swinging the pivoted blade to cutting position, the point of engagement between the operating means and pivoted blade being progressively farther from the pivot of the blade as the blade moves to full cutting position, thereby increasing the leverage as the cutting point approaches the free end of the moving blade, to insure a clean cutting action throughout the operative length of said blade.

20 2. The machine of claim 1 in which the operating means engages the pivoted blade by means of a pin and slot connection.

25 3. The machine of claim 1 with yielding means engaging the operating means to cause the pivoted blade to be pressed laterally against the fixed blade.

30 4. The machine of claim 1 with yielding means connected with the operating means and acting on the pivoted blade through said operating means and at a location remote from the pivot to cause the pivoted blade to be pressed laterally against the fixed blade.

35 5. A gummed tape serving machine comprising a tape feed device, a tape shearing device, a lever which by movement in one direction operates both the feed and the shearing devices, said feed device including a fixed pin, a ratchet, and a pawl actuated by the lever and which pawl by striking the pin is disengaged from the ratchet prior to the 40 cutting action of the shearing device, a spring for returning the lever to original position, and an independent spring for returning the shear to non-cutting position.

45 6. In a gummed tape serving machine, in combination, a tape shearing device having a fixed blade and a movable blade pivoted adjacent one end of the fixed blade, said movable blade resting normally below the path of the tape, spring means tending to retain said movable blade in normal position, a lever swingable in the same or a substantially parallel plane with that of said movable blade, and means operatively connecting said lever and movable blade whereby swinging of the lever in one direction will elevate said movable blade against tension of said spring means, to shear the tape, said spring means acting in a plane at an angle to that of the movable blade to cause continuous pressure of the latter against the fixed blade during the shearing operation.

7. In a gummed tape serving machine, in combination with a frame including opposite side members extending longitudinally in the direction of tape service, tape severing means

extending transversely of and between the side members and including a fixed blade and a swingable blade, a shearing lever pivoted intermediate the side members and operatively related to the swingable blade, and means connected with said lever and extending laterally outwardly of one side member in position to be operated to effect tape severance.

70 8. In a gummed tape serving machine, in combination with a frame including opposite side members extending longitudinally in the direction of tape service, tape severing means extending transversely of and between the side members and including a fixed blade and a swingable blade, a shearing lever pivoted intermediate the side members and operatively related to the swingable blade, said lever moving in the same or a substantially parallel plane with that of the swingable blade, and an operating member for said lever projecting laterally outside one side member of the frame.

75 9. In a gummed tape serving machine, tape severing mechanism including a fixed blade and a movable blade having an upward cutting stroke and normally lying below and clear of the tape path, a blade actuating member also below the tape path, a spring tending to resist upward movement of said movable blade and its actuating member, an operating lever adapted to operate said actuating member during the latter part of the movement of said lever in one direction, and a spring resisting movement of said operating lever in said direction, said lever being returned in the opposite direction first under the influence of both said springs and thereafter under influence of the second spring only.

80 10. In a gummed tape serving machine, in combination, a tape shearing device having a fixed blade and a movable blade supported adjacent one end of the fixed blade, a two-arm operating lever for said movable blade pivoted on an axis substantially parallel with that of the movable blade and having one arm operatively connected to said movable blade at the blade side of the latter's support, and means for moving the other arm of said lever in a direction opposite to the shearing movement of the movable blade to cause the latter to shear the tape against the fixed blade.

85 11. In a gummed tape serving machine, in combination, a tape shearing device having a fixed blade and a swinging blade pivoted adjacent one end of the fixed blade, an operating lever for said swinging blade pivotally fixed in a vertical plane spaced laterally from the blade pivot toward the opposite end of the fixed blade, said lever moving pivotally in a similar plane as the swinging blade but in the opposite rotative direction, means for so oppositely moving said lever about its pivot to cause the swinging blade to shear the tape against the fixed blade, and spring

means for returning the blade and lever to normal position.

12. In a machine for serving gummed strips for packaging and like purposes, a pair of feed rolls for advancing the strip between them, a lever having an operating and a return movement, gearing connections between said lever and said feed rolls, strip cutting means adapted to be actuated by said lever during the latter part of its operating movement, said gearing connections including a plurality of different sized gears intermediate the lever and the axis of one feed roll whereby the latter is geared up with respect to the lever, one gear having a ratchet wheel rigid with it, a pawl carrier coaxial with but angularly movable relatively to said ratchet wheel and operatively connected to said lever, a pawl pivoted on said carrier, spring means normally urging said pawl into engagement with the ratchet wheel, and a stationary stop in the path of the pawl so located as to effect disengagement thereof just prior to actuation of the strip cutting means by said lever, whereby the strip is left at rest during the cutting operation.

13. A gummed tape serving machine comprising a tape feed device, a tape shearing device, including a fixed blade and a movable blade having an upward cutting action and a gravitational return action, a lever which by movement in one direction operates both the feeding and the shearing devices, spring means to assist gravity in returning the blade to normal position and also for returning the lever to original position, means operatively disconnecting the lever and feed device prior to its actuation of the shearing device, and a return limit stop for said lever adjustably mounted adjacent the lever for varying the return thereof, to afford various lengths of cut tape as desired.

14. A machine for delivering tape comprising; feeding mechanism; cutting mechanism including a blade normally below the tape path and movable upwardly to cut, and a blade-operating lever; a control lever; and connections for successively actuating the feeding and cutting mechanisms by a single movement of the control lever in one direction, including a pawl and ratchet for the feeding mechanism, said pawl being positively operatively associated with the control lever, and means for positively disengaging the pawl prior to actuation of the cutting mechanism by said control lever.

15. In a gummed tape serving machine, in combination with tape feed means, a tape shearing device on the machine including a fixed blade and a movable blade pivoted adjacent one end of the fixed blade, a lever pivoted on the machine to swing in a similar plane as the movable blade and having a relatively long arm having a shifting point of engagement with the movable blade, said lever also

having a relatively short operating arm, whereby a relatively short angular movement of said operating arm effects a relatively greater angular movement of the movable blade.

16. In a gummed tape serving machine, in combination with tape feed means, a tape shearing device on the machine including a fixed blade and a movable blade pivoted adjacent one end of the fixed blade, said blades normally lying with their operative edges adjacent but at opposite sides of the path of the tape, a lever pivoted on the machine to swing in a similar plane as the movable blade and having a shifting point of engagement with the latter, and a common lever for operating the feed means and for pivotally moving said first-named lever to operate the movable blade.

17. In a gummed tape serving machine, in combination, a tape shearing device having a fixed blade and a movable blade pivoted adjacent one end of the fixed blade, said movable blade resting normally below the path of the tape, spring means tending to retain said movable blade in normal position, a lever having arms of unequal lengths pivoted on the machine for swinging in the same or a parallel plane with that of said movable blade, cam means operatively connecting the longer arm of said lever and the movable blade, and separate means for moving the shorter arm of said lever thereby to swing the lever in a direction to elevate said movable blade against tension of said spring means, said blade having a multiplied movement relative to that of the short arm of the lever.

18. In a gummed tape serving machine, in combination with a frame and a support for a tape supply, tape shearing mechanism including a fixed blade and a movable blade, operating means for the movable blade, means to insure lateral shearing pressure between the blades, and a pair of rotary feed members, of less than tape width, to advance the tape from the supply past the shearing mechanism, said members being mounted for relative yielding movement in a separating direction and being normally urged into tape advancing relation.

19. In a gummed tape serving machine, in combination with a frame and a support for a tape supply, tape shearing mechanism including a fixed blade and a movable blade, operating means for the movable blade, means to insure lateral shearing pressure between the blades, and a pair of rotary feed members to advance the tape from the supply past the shearing mechanism, one of said members mounted on an axial member having inherent resilience and positioned relatively to the axis of the other member yieldably to urge said members into tape advancing relation.

20. In a gummed tape serving machine, in combination with a frame and a support for a tape supply, tape shearing mechanism including a fixed blade and a movable blade, 5 operating means for the movable blade, means to insure lateral shearing pressure between the blades, a pair of rotary feed members to advance the tape from the supply past the shearing mechanism, and variably 10 positionable guide means cooperating with said feed members, for tapes of different widths.

21. In a gummed tape serving machine, in combination; a frame; a support for a tape 15 supply; means providing a service path for the tape from said supply; tape severing means including a movable and a fixed severing element, operating means for the movable element, and means to insure lateral 20 shearing pressure between said elements; and upper and lower rotatable feed wheels to feed the tape from the supply past the tape severing means, said wheels being of a width substantially less than that of the tape 25 service path, and one of said wheels being mounted for bodily yielding movement relative to the other wheel in the direction at right angles to the plane of the tape and having means normally urging it into tape feed- 30 ing relation with the other wheel.

In testimony whereof I hereunto affix my signature.

LOUIS LINK.
